UNITED STATES PATENT OFFICE.

ALFRED E. KELLOGG, OF EL CENTRO, CALIFORNIA.

CONNECTER FOR LUBRICATING APPARATUS.

Application filed June 12, 1922. Serial No. 567,591.

This invention relates particularly to a tip for use in connection with an adapter connected to a grease gun for supplying grease to a lubricating system.

5 An object of this invention is to provide means whereby, when the tip is not cooperating with the adapter, the orifice through the tip which admits the grease to the lubricating system will be entirely closed and hidden from view, and protected from dirt or foreign substances.

Other objects, advantages and features of manufacture.

15 Another object is to provide novel means for holding the adapter in engagement with the tip when the parts cooperate with each other to supply grease to a lubricating system.

Other objects, advantages and features of 20 invention may appear from the accompanying drawing, the subjoined detail description and the appended claims.

The accompanying drawing illustrates the invention.

25 Figure 1 is an elevation showing the tip in position on a fragment of machinery to be lubricated.

Fig. 2 is a section on line x^2 , Fig. 1.

Fig. 3 is a perspective view of the adapter 30 detached from the tip.

Fig. 4 is a central vertical section through the adapter and tip showing the parts in position for use.

Fig. 5 is an axial section analogous to Fig. 25 4 with the adapter detached from the tip.

Fig. 6 is a cross section on line x^6 , Fig. 4.

Fig. 7 is a plan view of the tip.

Fig. 8 is an elevation of the tip core.

40 The tip 1 is adapted to be mounted on a grease cup or attached to the inlet of a lubricating system, to receive grease under pressure from an adapter 2 which may be detachably secured to said tip. The tip 1 comprises a cylindrical sleeve or closure 3 which is slidably and rotatably mounted on the stationary conducting core 4 which is threaded at one end as at 5 for connection with the grease hole a of an oiling system.

45 The core 4 is provided with a shoulder 6 that serves as a stop for the inturned edge 7 of the sleeve 3 which is enlarged at its lower end to receive said shoulder 6 and to form a spring receiving chamber. An expanding spring 8 encircling the upper part of the core 4 in said spring receiving chamber and operating between the shoulder 6 and washer

9 which latter bears against a fiber washer 9' fitted to shoulder 10 in the sleeve 3, yieldingly holds the sleeve 3 in inlet closing position as shown in Figs. 1 and 2 where it is shown as closing a plurality of transverse grease admitting inlets or holes 11 that communicate with the bore 12 of the core 4 which extends longitudinally of the core and is open at the periphery of the core a short distance from the upper end of said core.

50 The core 4 is also provided with a wrench seat 13 for mounting the tip.

The end 14 of adapter shell 2' has an interior enlargement 15 to form a seat 16 for the retaining plate 17; also fitted into the enlargement 15 are the end plates 18 between which and the plate 17 is interposed a flexible packing 19; and through these plates and packing is an opening through which are extended the flexible tube 20 and metallic reinforcing tube 21, which encases the flexible tube 20. The tube 20 is preferably of annealed copper, and is adapted to be connected to a grease gun containing a supply of 55 grease.

Tube 20 has an enlarged end 22 that is fitted to the bottom of plate 17 so that the tube will be anchored in the adapter shell 2'.

60 The end 14 of the adapter is threaded to receive the cap 23 which is provided with a central opening adapted to fit over the flexible tubes 20, 21; and extending upward from the cap 23 and integrally connected thereto is a cylindrical reinforcing extension 24 that surrounds a portion of the tubes 20, 21. The cap 23 when threaded onto the shell 2' compresses the flexible packing against the plate 17.

65 The connection of tube 20 to the cap 23 and associated parts is such as to prevent leakage of a lubricant from the end 14 of the adapter 2; and such connection permits the adapter to be turned on the tube to attach it to the tip 1.

70 A leather washer 25 frictionally engages the inner wall of the adapter shell 2' and is adapted to be forced against the closure 3 when the tip and adapter are connected together, by means of the spring 26 which is mounted between the retaining plate 17 and a steel washer 27 that bears against the leather washer 25. Said washers 25, 27 are provided with central orifices 28 through which the upper end 29 of the core 75 4 protrudes when spring 26 forces the closure 3 and washers 25, 27 downward. The upper

end 29 of the core and the top of the sleeve 3 are rounded so that foreign substances may be easily wiped off and as shown in Fig. 2, there is no groove at the junction of the parts 3 and 29 to form a retainer for such foreign substance.

The leather washer 25 frictionally engaging the shell 2' serves to retain the spring 26 in mounted position when the adapter is disengaged from the tip.

The closure 3 is mounted on the core 4 by first inserting in the bore of said closure the fibre washer 9', washer 9 and spring 8, and then so positioning said closure and contained parts on the core 4 and rolling or otherwise turning in the edge 7 of the closure so that said edge will cooperate with the shoulder 6 to hold the closure in inlet closing position, as shown in Fig. 2.

In practice the adapter will be connected to the tip by first placing it in position so that the retainer lugs 30 which are formed as inturned portions of the adapter shell 2', are at right angles to the extensions 31 of the tip, and so that the extensions 31 are adjacent the cutaway portions 32 at the bottom of the adapter shell 2'; then the adapter is forced downward until the end 29 of the tip 1 enters the spring chamber 33 of the adapter 2 a sufficient distance so as to uncover the inlets 11; and then the adapter is turned until the sockets 34 on the underside of extensions 31 are seated over the protrusions 35 formed on the lugs 30 of the adapter shell 2'; and when so seated the adapter is secured in place on tip 1 by upward pressure of spring 26, that holds the protrusions 35 of the lugs 30 in the sockets 34.

This connection of the adapter to the tip permits lubricant to be forced through the tube 20, chamber 33, inlets 11, and thence through the hole 12 to the inlet *a* of the oiling system.

The leather washer 25 prevents any lubricant from escaping between it and the side wall of the adapter shell 2'. When the adapter is disengaged from the tip, the spring 8 of the tip immediately forces the sleeve 3 upward so as to automatically close the grease admitting inlets 11, thereby preventing dust and dirt or any foreign substance from getting into the oiling system.

I claim:

1. A connector for lubricating apparatus, having in combination, an adapter having a shell; a tip adapted to be received in the shell of said adapter and comprising a core provided with a longitudinal bore, said core having transverse holes communicating with said longitudinal bore, and a sleeve slideable on said core and adapted to close said transverse holes when the adapter is removed from the tip, said sleeve and core having their upper ends rounded.

2. A tip for lubricating systems comprising a core provided with a grease admitting inlet; means arranged around said core and adapted to normally close the grease admitting inlet; and means mounted between said core and said first mentioned means to normally hold said first mentioned means in an inlet closing position.

3. A connector for lubricating apparatus having in combination an adapter; a tip comprising a core having a grease inlet and a stop; a closure mounted on said core and being enlarged at one end to receive said stop; means whereby said closure is depressed so as to expose said grease inlet when cooperating with said adapter, and means whereby said grease inlet is closed by said closure when said tip is disengaged from said adapter.

4. A tip for lubricating systems comprising a core provided with a shoulder and having a grease inlet; a sleeve encircling said core, accommodating said shoulder with loose play so that the sleeve may be moved along the core, and having an inturned edge to engage the shoulder to prevent withdrawal of said core; said sleeve being adapted to be slid on said core to open and close the inlet; and a spring to yieldingly hold the sleeve in inlet closing position.

5. The tip set forth having a core provided with a shoulder and a longitudinal bore and transverse holes open to the bore; said bore extending from one end only of the core to said inlets; a sleeve slideable over the shoulder and on the core to close the holes when the sleeve is positioned near the closed end of the core; and to open the holes when the sleeve is slid from said closed end; and a spring operating between said shoulder and sleeve to hold the sleeve normally in hole closing position.

6. A tip for lubricating systems comprising a core having a grease inlet and a shoulder; a sleeve provided with a shoulder slideably mounted on said core and having an inturned edge adapted to engage the shoulder on said core; and means operating between the shoulder on said core and the shoulder on the sleeve to normally hold said sleeve in inlet closing position.

7. A connector for lubricating apparatus, having in combination an adapter having a shell provided with lugs; a tip adapted to be received in the shell of said adapter and comprising a core provided with a longitudinal bore; said core having transverse holes communicating with said longitudinal bore; means adapted to close said transverse holes when the adapter is removed from the tip; extensions on said core adapted to be engaged by said lugs; and means adapted to move said closure means so as to open said transverse holes when the lugs and extensions are in engagement.

8. A connector for lubricating apparatus,

- having in combination an adapter having a shell provided with lugs; a tip adapted to be received in the shell of said adapter and comprising a core provided with a longitudinal bore; said core having transverse holes communicating with said longitudinal bore; means adapted to close said transverse holes when the adapter is removed from the tip; extensions on said core adapted to be engaged by said lugs; and means adapted to move said closure means so as to open said transverse holes when the lugs and extensions are in engagement, said last mentioned means also being adapted to hold said lugs and extensions in frictional engagement. 9. A connector for lubricating apparatus, comprising an adapter having a shell provided at one end with a seat; a retaining plate in said seat; a flexible packing; a cap threaded on said shell and adapted to compress the packing onto said plate; a leather washer in said shell; a spring between said washer and said plate; means extending through said cap, packing and plate and adapted to be connected to a supply of grease; and a washer and said plate; and means extending through said cap, packing and plate and adapted to be connected to a supply of grease. 10. A connector for lubricating apparatus, comprising an adapter having a shell provided at one end with a seat and at its other end with lugs; a retaining plate in said seat; a flexible packing; a cap threaded on said shell and adapted to compress the packing onto said plate; a leather washer in said shell; a spring between said washer and said plate; means extending through said cap, packing and plate and adapted to be connected to a supply of grease; a tip connected to a part to be lubricated and adapted to be received in said shell; and extensions on said tip to be engaged by said lugs. 11. In testimony whereof, I have hereunto set my hand at El Centro, California, this 2nd day of June, 1922.

ALFRED E. KELLOGG.
